US00D442492S

(12) **United States Design Patent** (10) Patent No.: **US D442,492 S**
(45) Date of Patent: **** May 22, 2001**

(54) **BOTTLE**

(75) Inventors: **Suppayan M. Krishnakumar**, Nashua, NH (US); **Jeff Lichtman**, Evanston; **Jeffrey L. Pattee**, Palatine, both of IL (US); **David P. Piccioli**, Auburn, NH (US); **Christopher D. Rowe**, Barrington; **Tia-Maria Smith**, Chicago, both of IL (US)

(73) Assignee: **Stokely-Van Camp, Inc.**, Chicago, IL (US)

(**) Term: **14 Years**

(21) Appl. No.: **29/078,534**

(22) Filed: **Feb. 9, 1998**

(51) LOC (7) Cl. **09-01**

(52) U.S. Cl. **D9/537**

(58) Field of Search D9/520, 537, 540, D9/550, 551, 553; 215/381, 383, 384

(57) **CLAIM**

The ornamental design for a bottle, as shown and described.

DESCRIPTION

FIG. 1 is a perspective view of a bottle showing our new design;

FIG. 2 is a front elevational view thereof, the rear being identical;

FIG. 3 is a side elevational view thereof, the opposite side being identical;

FIG. 4 is a bottom plan view thereof;

FIG. 5 is a perspective view of a second embodiment of FIG. 1;

FIG. 6 is a front elevational view of FIG. 5, the rear being identical;

FIG. 7 is a side elevational view of FIG. 5, the opposite side being identical;

FIG. 8 is a bottom plan view of FIG. 5;

FIG. 9 is a perspective view of a third embodiment of FIG. 1;

FIG. 10 is a front elevational view of FIG. 9, the rear being identical;

FIG. 11 is a side elevational view of FIG. 9, the opposite side being identical;

FIG. 12 is a bottom plan view of FIG. 9;

FIG. 13 is a perspective view of a fourth embodiment of FIG. 1;

FIG. 14 is a front elevational view of FIG. 13, the rear being identical;

FIG. 15 is a side elevational view of FIG. 13, the opposite side being identical;

FIG. 16 is a bottom plan view of FIG. 13;

FIG. 17 is a perspective view of a fifth embodiment of FIG. 1;

FIG. 18 is a front elevational view of FIG. 17, the rear being identical;

FIG. 19 is a side elevational view of FIG. 17, the opposite side being identical; and,

FIG. 20 is a bottom plan view of FIG. 17.

The broken line environmental showing is for illustrative purposes only and does not form part of the claimed design.

1 Claim, 10 Drawing Sheets
